OVERFLOW DEVICE

Walter Carl Stollberg, Quincy, Ill.

Application October 20, 1933, Serial No. 694,476

2 Claims. (Cl. 158—37)

My invention relates to devices for preventing the overflow of fuel oil in the burner well of a gaseous fuel burner and it primarily has for its objects to provide a device for that purpose which will be of a simple, effective and inexpensive construction, one which will be non-siphoning and one which will not give off objectionable odors.

Further, it is an object of my invention to provide a device for the purpose stated in which provision is made whereby the over-flow pipe of the device may be closed off when it is desired to prime the burner.

Further, it is an object to provide an over-flow device of the character stated in which the level of the over-flow tube's outlet may be adjusted higher or lower in order that the fuel level in the burner well may be raised or lowered.

Further, it is an object to provide an over-flow device in which air vapors, which may be formed due to excessive heat, may be condensed in the device and run out through an over-flow discharge pipe.

Other objects will in part be obvious and in part be pointed out hereinafter.

To the attainment of the aforesaid objects and ends, the invention still further resides in the novel details of construction, combination and arrangement of parts, all of which will be first fully described in the following detailed description, and then be particularly pointed out in the appended claims, reference being had to the accompanying drawing in which:—

Figure 1 is a vertical section of a burner with my invention applied.

Figure 2 is an enlarged vertical section of a slightly modified construction of my device.

Figure 3 is a top plan view of the parts shown in Figure 2.

Figure 4 is a cross section on the line 4—4 of Figure 1.

Figure 5 is a vertical section of another modification of the invention.

In the drawing in which like numerals and letters of reference designate like parts in all of the figures, 1 represents the oil well of the burner (the burner may be of any well-known construction), 2 the oil chamber housing, 3 the float valve, 4 the lower sediment chamber into which the fuel oil is delivered and from which it passes via the float valve 3 into the sediment chamber 7 of the housing 2. The housing 2 has a duct 8 that communicates with the burner-well oil-feed tube 9 that is secured in the oil chamber housing by means of a compression sleeve 11 and compression sleeve lock screw 10.

12 is the sediment chamber head through which the needle valve unit 6 passes for controlling the flow of fuel oil into the chamber 7. Secured to the head 12 in any suitable manner is a duct 13 which has a base 14 that carries the outer casing 15 of my device. The casing 15 encloses an overflow chamber 37 and it has an inlet bore 16 in which is vertically adjustably mounted the overflow pipe 17. The pipe 17 is held in its position by means of a compression sleeve 18 and compression sleeve lock screw 19. The head 12 which carries the duct 13, etc. is held in place by the valve head 39 which is threaded at 40 to screw into the threaded part 41 of the well 2; 46 indicates the float-valve stem guide, 47 the valve stem, 42 the float bar, 43 the float connecting rod from the bar 42 to the float 44, the latter being located in the float chamber 45. The operation of the parts 3, 41, 42, 43, 44 and 45 may be the same as those of the respective parts 8, 9, 7, 6, 5, 20 and 4 shown in Letters Patent #1,569,638 to Sheer, January 12, 1926, since they, per se, are no part of the present invention and no claim is laid thereto.

In the embodiment of the invention shown in Figures 1 and 2 the over-flow casing has a neck 20 to which is connected the over-flow pipe 21 that conveys the over-flow oil from the chamber 37.

In order to prevent siphoning the casing 15 may be provided with one or more vents 22.

In the embodiment of the invention shown in Figure 1 the upper end of the casing 15 is internally threaded as at 23 to receive a screw plug 24 which has a tapered shut-off member 25 that may be used to plug the upper end of the overflow pipe 17 when it is desired to prime the burner. The plug 24 is provided with a screw driver slot 26 for manipulation purposes.

27 is a slot for a wrench whereby the compression lock-screw 19 may be turned.

Instead of screwing the plug 24 into the casing 15 the arrangement shown in Figure 2 may be employed. In Figure 2 those parts which correspond to like parts in Figure 1 bear the same reference numeral plus the index letter "a". The plug 24a is not threaded into the casing 15a, but is slidably mounted thereon so that it may be forced toward the upper end of the pipe 17a by pressing on the finger knob or button 28 against the tension of a light spring 29. The plug 24a is held from movement out of the casing 15a by means of a threaded collar 30 which has holes 31 for a spanner wrench. By this arrangement it is impossible to close the end of the 55

pipe 17a and leave it closed accidentally as might be the case in the embodiment shown in Figure 1, since as soon as the operator takes his finger off the button 28 the spring 29 will force the plug 24a away from the pipe 17a.

In Figure 2 the casing 15a is shown connected with a duct 33 that communicates with the oil feed line and the burner-well oil-feed tube through the use of ordinary pipe fittings and couplings not shown. The duct 33 is connected with the casing 15a by means of a threaded collar 32 which corresponds to the base 14, while the duct 33 corresponds to the duct 13 in Figure 1.

In Figure 5 is shown another modification of the invention. In this figure the over-flow pipe 17b is threaded at 34 into the base 14b and the casing 15b is removably threaded into the base, the casing 15b having openings 38 in its threaded end to register with the over-flow pipe 21b that is carried by an over-flow neck 35 of the base 14b. In this embodiment also the casing 15b is provided with the tapered plug 25b so that by unscrewing the casing 15b and inverting it as shown in dotted lines in Figure 5 it may be used as a temporary closure for the pipe 17b when it is desired to prime the burner.

In the embodiment shown in Figure 5 those parts which correspond in purpose and function to like parts in the preceding figures bear the same reference numeral plus the index letter b.

The oil level is indicated in Figure 1 by line 36.

From the foregoing description, taken in connection with the accompanying drawing, it is thought that the complete construction, arrangement and advantages of my invention will be clear to the art to which it appertains.

What I claim is:

1. In combination with a liquid fuel burner, a constant maximum level fuel feeding means therefor including a housing having an inlet com-

partment communicating with the source of fuel, a sediment compartment communicating with the burner, a threaded passage connecting said compartments, a detachable cover plate forming a wall of said sediment compartment and having an upwardly extending conduit projecting therefrom in communication with the sediment chamber and an opening in axial alignment with said threaded passage, a valve unit extending through said opening and into engagement with said threaded passage to control the flow of fuel between said compartments and to clamp said cover plate in place, and an overflow device connected to said conduit and operatively positioned relative to said burner to prevent flooding thereof upon the fuel level exceeding said maximum level.

2. In combination with a liquid fuel burner, a constant maximum level fuel feeding means therefor including a housing having an inlet compartment communicating with the source of fuel, a sediment compartment communicating with the burner, a threaded passage connecting said compartments, a detachable cover plate forming a wall of said sediment compartment and having an upwardly extending conduit projecting therefrom in communication with the sediment chamber and an opening in axial alignment with said threaded passage, a valve unit extending through said opening and into engagement with said threaded passage to control the flow of fuel between said compartments and to clamp said cover plate in place, an overflow device connected to said conduit and operatively positioned relative to said burner to prevent flooding thereof upon the fuel level exceeding said maximum level, and manually actuated means for rendering said overflow device inoperative to permit flooding for priming purposes.

WALTER CARL STOLLBERG. 40
